UNITED STATES PATENT OFFICE.

HAMMOND V. HAYES, OF CAMBRIDGE, MASSACHUSETTS.

HOTEL TELEPHONE SYSTEM.

SPECIFICATION forming part of Letters Patent No. 395,137, dated December 25, 1888.

Application filed November 5, 1888. Serial No. 290,013. (No model.)

To all whom it may concern:

Be it known that I, HAMMOND V. HAYES, residing at Cambridge, in the county of Middlesex and State of Massachusetts, have invented certain Improvements in Hotel Telephone Systems, of which the following is a specification.

My invention relates to systems of hotel-signaling; and its object is the establishment 10 of reciprocal telephonic communication between the several rooms of any building or group of buildings—such, for example, as the different departments of a factory and some central point. To accomplish this it is essential 15 that the central station shall be able to send call-signals to each and all of the several sub-stations; that each sub-station or outlying room shall be so provided that it can send call-signals to the central station, and 20 that when in either case the attention of the second party is attracted telephonic conversation can be carried on in either direction.

It is further in many cases desirable that 25 the usual call-bell and annunciator-wires of a hotel shall be made available without material change, this being especially important in view of the fact that it is both expensive and frequently difficult to run ground-wires in each room for the telephone-set and for 30 the calling by the central point of the several rooms. Most hotels are so wired for the existing calling systems that another wire could only be introduced by removing a portion of the plastering or floor, and often, especially 35 in the country, it is difficult to construct a number of trustworthy ground-connections. Moreover, it is not feasible to dispense with the ground-wires at each room and in lieu thereof to use the battery or return wire for 40 telephonic purposes also, if the said battery-wire be arranged as usual, for two reasons: in the first place, the battery would in that case have its circuit closed through such telephones as at any moment might be in use, 45 and the call-signaling would thus tend to inefficiency for want of a sufficient amount of current; and, in the second place, the act of signaling the central office would cause a redistribution of the battery-current and 50 disturb any telephonic conversation which at the moment might be going on. These con-

siderations have led me to devise an arrangement of telephonic and signaling circuits and apparatus which dispenses with individual ground-wires at the several rooms, which employs practically the simple ordinary arrangement of main and battery wires, and can therefore, without great expense, be substituted for or superimposed upon existing annunciator systems, while the difficulty which I have stated has been in the way of such employment is removed by changing the position and relation of the calling-battery, so that while the main battery or return wire, or a portion thereof, is in all cases utilized as 65 one side of the talking-circuit, the battery is no longer included in such circuit, but is merely attached thereto at some point, and can therefore be used in calling over other lines in its full force.

My invention comprehends the organization in a concrete system of a number of individual electric lines radiating from a central place or point to a number of rooms or other outlying points, all of which are provided 75 with a common return-wire, which serves also as a battery-supply wire for use in signaling from the several rooms to the central station. At each room is provided a call-receiving bell, buzzer, or vibrator, means for sending calls, 80 a telephone, and a manual automatic switch for transferring the circuit of the direct room-line from the call-receiver to the telephone, and vice versa.

At the central station I provide a visual or 85 other indicator to receive room-calls connected with the several direct lines, and telephones and call-sending appliances connected with the central-station end of the common return-wire, which is normally open or disconnected, but which is adapted by means of a conducting-cord and plug and a spring-jack in the circuit of each room-line, or any other well-known appliance, to be united with the central-station end of any of the said individual room-lines, for the purposes of sending outgoing call-signals or of conversation, constituting, when so united, a temporary metallic circuit in which a given room and the central point are the two corresponding stations.

At any suitable point of the return or battery-supply wire I connect a branch to earth,

in which is included a calling-battery of sufficient strength to operate the central-station annunciator from the most distant room. When the battery is so arranged in a branch 5 to earth, it is evident that it can never be short-circuited in the temporary metallic talking-circuit. Each individual room-line is normally grounded at the central station after passing through its spring-jack and annunciator. At the several rooms the said individual room-lines are normally connected through the call-instrument, and by means of the switch, with the common return-wire, and as the current of the battery would otherwise 10 divide itself between the several room-lines, the said battery being practically short-circuited through the said lines and their central-station terminal, earth, a suitable resistance sufficiently high is interposed in each 15 individual line at some point in the call-receiving branch, where it can be cut out when the switch is changed to the telephone. The battery is by such means kept from wasting away unnecessarily, and is maintained at all 20 times in good order. In sending call-signals from any room to the central station, a key is pressed which shunts the call appliance and resistance, and thus directs the battery-current practically with its entire force through 25 the annunciator of that line at the central station.

In sending calls from the central station to any room the otherwise detached plug constituting the normally open end of the common return-wire is thrust into the spring-jack of the desired line. The said line is thereby disconnected from its normal central-station ground, and the call now being sent by the magneto-generator and signaling-key or otherwise in the metallic circuit formed of the remainder of said line and a portion of the return-wire causes the call-receiving appliance—which with the resistance is included in such metallic circuit—to give the alarm, and by 35 turning the switch at the room end of the line and substituting the telephones for the sending apparatus at the central-station end conversation can then be carried on; and should any other room desire to send in a call 40 during conversation there is nothing to prevent the battery being simply branched to the return-wire, so that its current will traverse during the call-sending act that portion only 45 of the common return-wire which intervenes between the key of the room now sending the call and the point where the battery branch touches the main return-wire.

It is sometimes necessary to send an alarm (as, for instance, in cases of fire) from the 50 central point or office to all the rooms at once, and for this purpose I provide a spring-jack in the main central-station ground-wire of the room-lines. When this operation is to be performed, the plug end of the common return-wire is thrust into the ground-wire spring-jack, and the calling-current from the central-station magneto is thus divided between

a group of lines and the alarm given at once to the several stations connected with said lines.

The drawings show in diagram a hotel system comprising a central station, a number of rooms or outlying stations, individual lines connecting the rooms with the central station, and a common return-wire entering each 75 room, and serving also as a battery-wire. Four rooms only are shown, these being sufficient to illustrate the invention. They are respectively indicated by the letters D, E, F, and G. At the rooms D and E the entire apparatus and circuit arrangement are shown in detail, while at the remaining rooms, F and G, the inclosing-case and manual switch-handle only are shown, all of the parts being in practice inclosed within the said case. The 80 rooms are connected by wires 1, 2, 3, and 4 with the central station, C, where they respectively pass through spring-jacks s, and then each through its own annunciator d to a main ground-wire, 31, leading to earth at M. The 85 several annunciator-drops are preferably grouped in a suitable case, A.

At the several rooms the individual or direct wires pass through the room apparatus m to a permanent connection, controlled, however, as to its precise route by a suitable switch with a common return-wire. The return-wire w runs to each of the group of rooms branching into each room, and then continues to the central station, C; here it 95 is ordinarily open, terminating in a conducting-cord, f, having a connecting-plug, p, which can be introduced at will into the spring-jacks s of any of the room-lines. The cord f connects with the main wire w through a key 100 or switch, k, and the office-telephones, or the room-calling devices, are included in circuit alternatively, according to the position of the said key. For this purpose I have shown two branches of the return-wire w between the 105 key k and the point x on the said wire.

From x one branch leads by wire 115 through the magneto-generator g and wire 16 to the front contact, a, of the key, and at a this branch is open at all times, except when the 115 key is depressed. The other branch leads from the point x through the transmitting and receiving telephones T and t, and by wires 9 and 10 to the resting or back contact o of the key with which it is in normal contact. 120 The transmitter T is shown as connecting with the line-wire w by means of an induction-coil, i, and is itself in circuit with the primary helix of said coil and with a local battery, b'; but on short lines the induction-coil may be 125 dispensed with and a battery included with the transmitter in the main line.

At any convenient point on the return-wire w a branch, w', may be attached thereto, which branch leads through a calling-battery, 130 B, to earth M. This earth and battery branch is really another terminal of the said return-wire, and while, as shown, it may be placed at the point thereof which is most distant

from the central station, it is also evident that this location is only adopted for convenience of illustration, and that the earth branch may be placed at any other convenient point 5 and connected, as indicated in dotted lines at *b*, for, being an earth branch, it can exercise no influence over the metallic circuit when made up of a portion of the return-wire *w* and any one of the room-wires for outward 10 calling and conversation, and is therefore available for use by other rooms to supply current for calling the central station, even when the main return-wire is in use by some one room, and this irrespective of the special 15 location of its connection with the said main return-wire. In the diagram, at rooms 4 and 3, represented, respectively, by *D* and *E*, the disposition of the circuits and apparatus in the interior of the case *m* is shown.

20 At room *D* the line No. 4 divides into two terminal branches. This station is supposed to be in the act of communication with the central station. Consequently the switch *y*, which is in permanent connection with the return-wire *w*, has been brought into contact with plate 1, which terminates the telephone branch *u* of line 4; which branch diverges from the main line at *v* and passes through the telephone *m'*. From a point on this branch between the telephone and the point of divergence *v*, a sub-branch leads to a call-key, *k'*. This key has no back-contact stop, but its front contact leads by wire 29 to the return or battery wire direct, and when the key is 25 depressed the room-line is brought into connection with the return-wire, and the battery current, being thereby furnished with a low-resistance route, traverses the same through the line-annunciator at the central station and gives the call. When a line is quiescent, the switch *y* makes contact with the lower plate, *h*, this being the terminal of the call-apparatus branch *q*. This branch, diverging from the main line at *v*, is led through the call-magnet *c* and resistance *r* to the said terminal. 30 When the switch is on the lower branch plate, as is shown in *E*, the line is at rest and a call from the central point may be received.

35 In practice the wire 28, uniting the switch to the return-wire *w*, is dispensed with, and the switch is united by a local wire, 27, to wire 29, which leads from the said return-wire to the key-contact. Thus, but one wire from the return *w* to any room is necessary. In practice, also, the switch *y* may be provided with a retracting-spring holding it on the resting-contact *h*, and capable of pulling it back to the said contact when removed therefrom. 40 When so arranged, it is required that the operator shall hold the latch of the switch down during conversation. Or the said switch may be of the well-known automatic or gravity type, in which case it will be necessary to provide a suitable weight to hang on the latch when not in use. In such a contingency it 45 will be well to add a receiving-telephone, which can serve as the operative weight, in which

case the switch-connections would have to be reversed or its fulcrum placed at the extreme inner end.

I prefer to use a single magneto-telephone, *m*, at each room, both as transmitter and receiver; but a battery-transmitter may be added, in a manner well understood, if desired. The function of the resistance *r* in the call branch at each room is to prevent the battery from running down, as would be the case were the said resistance absent. These resistances may each be from two to three thousand ohms, according to the number of rooms, and assuming one hundred rooms, and at each a resistance of three thousand ohms, the joint resistance presented by the system to the battery would be thirty ohms.

A spring-jack, *s'*, is included in the main ground-wire at the central point. To send a general alarm, the plug terminal *p* of the return-wire is inserted in the said jack, the magneto-machine *g* operated, and the key *k* pressed. The call is thus sent to all the rooms having lines terminating in the said ground-wire. Where there are many rooms a large magneto-machine actuated by power may be profitably employed. Several groups of lines may be employed, each group having an independent call-battery, an independent central-station ground, and an independent return-wire.

If desired, instead of the central-station magneto-generator *g*, a battery and pole-changer may be employed; but the generator is preferable, as requiring no attendance.

In the figure the central station is shown as being in correspondence with room 4. The switch at said room is on the telephone branch, and the central-station return-wire plug is in the jack of line 4. Thus a metallic circuit is provided for talking, as may easily be traced. The other rooms desiring to call the central station may do so by pressing their keys *k*, and will then press down the latches of their switches and talk. The central station desiring to call any of the rooms places the plug *p* in the proper spring-jack, turns the crank of the generator, and at the same time presses the key *k*.

Having now described my invention, I claim—

1. A hotel or factory telephone system comprising a central station, a series of rooms or sub-stations, a series of direct lines, each extending from one of the rooms to the central station and there terminating in an earth-wire after passing through a spring-jack and annunciator, a common return-line extending from the central station and branching into all of the rooms, the said line being normally open or disconnected at the central station, an earth branch including a calling-battery connected, as described, with said return-line, a switch and connections therefor at each room permanently united with said return-line and normally connecting the same with the direct line through a call-receiving instrument, and a resistance but adapted to

transfer the said connection to a second branch of said direct line, including a telephone, a key or button arranged to unite the direct line with the return-line, shunting the several 5 appliances of the former, and thereupon to direct the major part of the battery-current over the said direct line for the purpose of operating the central-station call-annunciator, and means for uniting the central-station end 10 of the common return-wire to any one of the direct wires for the purpose of sending outgoing signals and to establish a talking-circuit, substantially as described.

2. In a hotel or factory telephone system, a 15 series of direct lines converging from a number of rooms or sub-stations to a central-station, each line being grounded at the said central station after passing through a switching and call-receiving device, an independent 20 line extending from the central station to a distant ground-connection, the central station end thereof being normally open, but provided with connecting call-sending appliances and telephones, whereby it may be connected with and operated as a return-line in 25 conjunction with any of the said direct lines, a switch at each room uniting the direct line thereof with the said independent line alternatively, according to the position of said 30 switch, through a call-device branch or a telephone branch, a calling-battery included in the earth-connection of the independent line, a resistance included in the telephone branch at each room to prevent short-circuiting of 35 the battery, and a normally open key adapted to short-circuit or shunt the said resistance, and thereupon to direct the battery-current over the direct line for the purpose of sending the central-station call, all in combination. 40 and substantially as described, whereby the independent line may be utilized as a battery-supply line for all of the room-lines, and also as a return-wire for any line in sending outgoing signals and for telephonic communication. 45

3. The combination, in a hotel telephone

system, of the group of direct lines converging from the several rooms to the central office and there provided with earth terminals, the battery-wire grounded on one side of 50 the said battery and connected by branch wires on the other side of said battery with the outer end of each of the direct room-wires, the said battery-wire further extending to the central station, and being adapted to serve 55 also as a return-circuit for any one of the direct lines in sending outgoing calls and in telephony, and suitable resistances—one for each room—interposed between each direct line and its connection with the battery-line, 60 whereby short-circuiting of the said battery is prevented, substantially as hereinbefore described.

4. The combination, in a hotel telephone system, of a group of direct lines adapted for 65 signaling and for telephonic conversation converging from a number of rooms to a central station, a common ground-wire at the said central station for all of the said lines, a spring-jack included in the said ground-wire, 70 a common return-wire branching into all of the said rooms and normally connected by its branches with each of the said direct lines through a resistance, the said wire being normally open at its central-station end and provided with a terminal plug, whereby it may be united with the said spring-jack, so as to constitute a common metallic return for the group of direct lines, and a magneto-generator or its equivalent interposed in the said metallic circuit when so completed, whereby a general alarm may be sent from the central station to all of the said rooms, substantially 80 as described.

In testimony whereof I have signed my name 85 to this specification, in the presence of two subscribing witnesses, this 29th day of October, 1888.

HAMMOND V. HAYES.
